UNITED STATES PATENT OFFICE.

JOHN LINZ, OF PITTSBURGH, PENNSYLVANIA.

VENTILATOR.

Application filed April 12, 1927. Serial No. 183,123.

This invention relates to improvements in ventilators especially designed for windows and has for an object the provision of a ventilator which may be built in and form a part of a window sash or may be secured within the window frame independently of the sash.

Another object of the invention is the provision of a ventilator which includes a novel form of shutter and means for pivotally mounting the shutters within the ventilator frame, so that the shutters may be adjusted, the shutters being separated by partitions which are shaped to conform to the shape of the shutters.

Another object of the invention is the provision of means for conveniently and simultaneously adjusting the shutters to regulate the passage of air through the ventilator.

Another object of the invention is the provision of a ventilator which in addition to the above and other advantageous features, includes a frame which is constructed so as to receive a screen.

With the above and other objects in view, the invention further includes the following novel features and details of construction, to be hereinafter more fully described, illustrated in the accompanying drawings and pointed out in the appended claims.

In the drawings:

Figure 1 is a fragmentary elevation showing the invention applied.

Figure 2 is a vertical sectional view showing the invention applied to a window sash and the latter mounted within a window frame.

Figure 3 is a section taken substantially on the line 3—3 of Figure 1.

Figure 4 is an enlarged section on the line 4—4 of Figure 3.

Figure 5 is a section on the line 5—5 of Figure 4.

Figure 6 is a section on the line 6—6 of Figure 4.

Figure 7 is a fragmentary section taken on the line 7—7 of Figure 6.

Referring to the drawings in detail where-in like characters of reference denote corresponding parts, the reference character 10 indicates a ventilator frame or casing which may be arranged within a window frame, or may form a part of a window sash. For the purpose of securing the ventilator frame within a window sash, the sash which is in-

dicated at 11 is supplied with an auxiliary rail 12 which is spaced from the usual sash rail 13. The stiles and rails of the sash are provided with the usual grooves 14 for receiving the edges of the window pane 15, the rail 12 being provided with a similar groove 14a. The edges of the frame or casing 10 are provided with right angularly arranged flanges 16 which are received within the grooves 14—14a and are secured therein by any suitable means. The frame of the ventilator thus forms a part of the sash 11.

Pivotally mounted between the upper and lower horizontal members 17 of the frame 10, as shown at 18, are shutters 19. These shutters include arcuate walls 20 and end wings 21. Arranged between the shutters are partitions 22 whose outer edges are curved to conform to the curvature of the walls 20, as shown at 23, so that the shutters may be adjusted pivotally to regulate the passage of air through the ventilator and to provide a proper fit when the shutters are closed. Spaced from the end walls of the frame or casing 10 are supplemental walls 24 and 25 which have their outer edge portions curved as shown.

Extending from the wings 21 of the shutters are pins or studs 26. These pins or studs extend upwardly through arcuate slots 27 provided in one of the horizontal walls of the casing or frame 10 and are attached to a rod 28, so that when the latter is moved longitudinally the shutters will be simultaneously adjusted.

In order to conveniently effect this adjustment, one end of the rod 28 is toothed to provide a rack 29. This rack engages a pinion 30 which is mounted upon a shaft 31, the latter also having mounted thereon a pinion 32. This last mentioned pinion engages a toothed rack 33 carried at one end of a vertically movable rod 34. The rod extends downward through the frame or casing 10 and through the rail 12 and is movable within a guide 35 carried by the sash. It will be apparent that when the rod 34 is moved vertically, horizontal movement will be imparted to the rod 28 so as to adjust the shutters as previously mentioned. The wall 25 provides a housing within which the pinions 30 and 32 are arranged.

The inner end of the wall 25 and the inner end of the wall 24 are spaced from the adjacent edge of the frame or casing 10 and the vertical walls of this frame or casing

are provided with a flange 40 so as to provide a groove to receive the frame 41 of a screen 42. A unitary structure is thus provided which may be carried by the sash 5 which includes an adjustable ventilator for regulating the draft and a screen for preventing the passage of insects.

The invention is susceptible of various changes in its form, proportions and minor 10 details of construction and the right is herein reserved to make such changes as properly fall within the scope of the appended claims.

Having described the invention what is 15 claimed is:

1. A ventilator comprising a casing open at its front and rear and having spaced arcuate slots in one of its horizontal walls, shutters mounted for pivotal movement between 20 said walls concentric with said slots, a rod extending longitudinally of the casing, pins extending through the arcuate slots and connecting the shutters and rod and means associated with the rod to move the latter longitudinally to adjust the shutters.

2. A ventilator comprising a casing open at its front and rear and having spaced arcuate slots in one of its horizontal walls, shutters mounted for pivotal movement between 25 said walls concentric with said slots, a rod extending longitudinally of the cas-

ing, pins extending through the arcuate slots and connecting the shutters and rod, a rod disposed at right angles to the first mentioned rod and means operatively associated with said rods to move the first referred to rod longitudinally to adjust the shutters when the second mentioned rod is operated.

3. A ventilator comprising a casing open at its front and rear and having spaced 40 arcuate slots in one of its horizontal walls, shutters mounted for pivotal movement between said walls concentric with said slots, a rod extending longitudinally of the casing, pins extending through the arcuate slots 45 and connecting the shutters and rod, a rod disposed at right angles to the first mentioned rod, rack bars at the ends of each rod and gearing connecting the rack bars to move the first referred to rod longitudinally 50 to adjust the shutters when the second mentioned rod is operated.

4. The combination with a window sash having a glass receiving groove, of a bar extending across the sash and spaced from one end of said sash and also having a groove, a ventilator frame, a flange extending around the ventilator frame within the groove and means to secure the flange within the groove.

In testimony whereof I affix my signature.

JOHN LINZ.
